UNITED STATES PATENT OFFICE.

ODILON BRISBOIS, OF CHICAGO, ILLINOIS.

ENGINE STARTER.

Application filed June 18, 1923. Serial No. 646,034.

This invention relates to an engine starter of that type in which a driven member is caused to move longitudinally into coacting engagement with a member on the engine shaft.

Among the objects of this invention, it is contemplated to devise a starter in which the driven member does not begin its longitudinal movement until the motor has developed sufficient torque for the purpose of starting what is commonly known as a "stiff engine".

A further object of the invention consists in the provision of longitudinally shiftable means for the driven member having yieldable inclinations, so that the driven member may readily slip rearwardly when there is an abutting relation between it and the engine member.

It is also an object of this invention to utilize compressible means for frictionally holding the driven member with relation to its source of power during the operation of starting the motor.

It is more specifically an object of this invention to slidably mount a hollow sleeve upon a motor shaft and provide a slot in the periphery of said sleeve consisting of a short transverse portion and an inclined portion of yieldable inclination.

It is also an object of this invention to provide a starter in which there is a certain amount of yield upon a back-kick of the engine when the same is under the highest compression, in order to prevent damage to the motor upon reversal thereof.

It is a further object of this invention to overcome the objectionable abutting relation between the driven member and the engine member in a new and novel way.

With these and other objects in view which will become more apparent from the following description and disclosures, this invention comprises the novel structure and combinations hereinafter described and more particularly pointed out and defined in the appended claim.

In the accompanying drawings which illustrate a preferred embodiment of this invention and in which similar reference characters refer to similar features in the different views:

Figure 1 is an elevational view of a starting motor equipped with a starting mech-

anism involving my invention and showing a portion of an engine member consisting of a fly-wheel.

Figure 2 is an enlarged elevational view of the starting mechanism with the driven member in coacting relation with the engine member.

Figure 3 is an enlarged section on the line 3—3 of Figure 1.

Figure 4 is a section upon the line 4—4 of Figure 2.

Figure 5 is a development of the spiral slot in the sleeve.

In referring now to the drawings which illustrate a preferred embodiment of this invention, there is shown the usual motor 1 having a shaft 2 provided with a reduced outer end 3 forming a shoulder at the inner end of the reduced portion. A hollow sleeve provided with a bearing neck 4 to fit the reduced portion 3 of the shaft and an enlarged cylindrical portion 5 is slidably mounted upon the shaft, the bearing portion 4 being provided with diametrically opposite longitudinally extending slots or bifurcations for receiving a pair of diametrically opposite tongues or lugs 6 extending from a collar 7 secured to the end of the reduced portion of the shaft by a set screw 8 or the like, one of the lugs 6 being preferably keyed to the shaft, as shown in Figure 4. Therefore, as the shaft 2 is rotated, the tongues or lugs 6 which are nested in the bifurcations of the bearing neck 4 will cause the sleeve to rotate with the collar 7.

It should also be noted that the bearing neck 4 is not as long as the distance between the collar 7 and the annular shoulder at the inner end of the reduced portion, so that the sleeve has a certain amount of longitudinal play or movement. A coiled spring 9 surrounds the bearing neck 4 between the collar 7 and the enlarged cylindrical portion 5 of the sleeve, the purpose and function of which will hereinafter more fully appear.

A spiral slot is made in the periphery of the sleeve and consists of a short transverse portion 10 and an inclined portion 11 at approximately an angle of 25° to the straight transverse portion. This inclined slot portion 11 will allow a slippage along its surface and that will allow the pinion to recede upon a sudden impact. I may term such an inclination as yieldable. It

should however be understood that any other inclination may be used that will allow slippage against the side of the slot.

A driven member 12 in the form of a gear 5 is loosely mounted upon the shaft 2 within the cylindrical enlarged portion of the sleeve and is provided with a smooth hub portion at its inner end, from which a radial stud 13 projects into the spiral slot or guideway. 10 The inner end of the motor shaft is provided with a collar 14 and a coiled spring 15 of greater tension than spring 9 is positioned against the collar 14 and extends outwardly upon the motor shaft.

15 Figure 1 shows parts in normal position in which the stud 13 is resting in the transverse portion of the spiral slot. We will now assume that the motor is started. It will require several revolutions of the shaft before 20 the sleeve will cause sufficient longitudinal travel of the pinion 12 to bring the same into mesh with the gear 16 of the engine shaft; the transverse portion of the slot retarding longitudinal movement of the pinion to this 25 extent. In other words, the sleeve 5 will have to rotate until the radial projection 13 is brought into the inclined portion of the slot. This particular construction will allow the motor to acquire sufficient torque for the 30 purpose of starting a stiff engine, or, in other words, a new engine that has not been sufficiently used to produce a free and easy action.

As soon as the radial projection 13 is brought into the inclined portion 11 of the 35 slot, it will shift the driven member 12 longitudinally into mesh with the engine member 16 against the tension of the spring 15, which will be compressed and exert a longitudinal thrust in the opposite direction to 40 compress the spring 9. During the longitudinal travel of the driven member 12, the stud 13 will not travel to the end of the slot 11 but will stop a certain distance from the end of the slot, as shown in Figure 2; the 45 spring 15 resisting further longitudinal movement of the driven member or pinion 12, whereby the same may be held between two longitudinally yieldable forces while being rotated to start the engine.

50 Now, assuming that during the longitudinal travel of the pinion 12 toward meshing relation with the gear 16, the teeth of the pinion and gear 16 should come into an abutting tooth-on-tooth relation, in such a case 55 the inclination of the slot 11 is such that but slight longitudinal impelling force is exerted against the pinion 12, so that no serious impact or frictional binding will occur, and any undue impact will cause the pinion to 60 recede into the sleeve on account of the inclination of the slot 11, or the spring 9 may be compressed so the gears can always be readily brought into meshing relation.

If the engine should back-kick during the 65 operation of starting, an increased force will

be imparted to the pinion 12 which will overcome resistance of the spring 15 and rotate the stud 13 into the end of the inclined slot 11 before the motor will be reversed. It is well known that the greatest shock of back-firing occurs at the instant that the back-kick occurs when the engine is under the highest compression, and this shock at reversal will be absorbed largely through the extended part of the slot 11 through which the radial stud passes upon back-firing before the motor is reversed.

Besides affording a yield to the pinion 12 when there is a tooth-on-tooth engagement between it and the gear 16, the inclined slot 11 has another important advantage, especially in starting stiff or green engines. Assuming that the motor has been started and the operator has removed his foot from the switch, under the belief that the engine has been started, when the engine in fact has not been started. As soon as the operator stops the motor under such conditions, the impetus imparted to the pinion 12 by the spring 15 in conjunction with the rotation of the fly wheel gear of the engine due to its momentum will cause the pinion 12 to demesh and return to initial position. The inclination of the slot 11 facilitates this operation. Consequently when the motor is started again it can acquire sufficient torque before the pinion goes into mesh with the fly wheel to start the motor.

Another important feature arising from the particular slope of the slot is that a very short arc of rotation of the sleeve occurs while the pinion is going into mesh so that the chamfering of the gear teeth is greatly reduced. It is characteristic of this starter that the pinion can be easily and quickly brought into full meshing relation, and that the motor has acquired sufficient torque when this occurs to start any stiff engine.

I am aware that numerous details of construction may be varied through a wide range without departing from the principles of this invention, and I therefore do not purpose limiting the patent granted otherwise than necessitated by the prior art.

I claim as my invention:

In an engine starter comprising a motor shaft having a reduced end, a sleeve having a bifurcated bearing slidably mounted on said reduced end, a collar on said reduced portion having lugs extending into said bifurcation, a pinion mounted within said sleeve having a stud projecting radially therefrom, said sleeve having a spiral slot for receiving said stud, a spring between said sleeve and collar, and a second yieldable spring adapted to be put under compression during the longitudinal travel of said pinion.

In testimony whereof I have hereunto subscribed my name.

ODILON BRISBOIS.
